(57) CLAIM

The ornamental design for the pair of boots having removable anklets, as shown and described.

DESCRIPTION

FIG. 1 is a perspective view of the left boot of my new design for a pair of boots having removable anklets;
FIG. 2 is a left side view of the design of FIG. 1;
FIG. 3 is a right side view of the design of FIG. 1;
FIG. 4 is a front view of the design of FIG. 1;
FIG. 5 is a rear view of the design of FIG. 1;
FIG. 6 is a top plan view of the design of FIG. 1; and,
FIG. 7 is a bottom plan view of the design of FIG. 1 and wherein the right boot of my new design for a pair of boots having removable anklets is the mirror image of the left boot depicted in FIGS. 1-7.
